REMOVABLE SLIDE FASTENER POCKET
AND LEADER POCKET

Glen P. Heiner, Salt Lake City, Utah

Application June 20, 1936, Serial No. 86,218

10 Claims. (Cl. 43—32)

My invention relates to fly books for fishermen and has for its object to provide a removable leaf section for said fly books which carried a slide fastener pocket therein.

A further object is to provide a removable leaf section for build up fly books such as are shown in my copending application for build up fly books, Serial No. 86,219, filed June 20, 1936, in which the removable leaf section carries a pocket closed by a slide fastener and which pocket also has a transparent side through which the user may observe the contents without opening the pocket, if desired.

A still further object is to provide a removable leaf section of the class described, in which the slide fastener pocket is accompanied with a net pocket for carrying leaders. This also provides for a handy removable pocket section from a build up fly book when desired.

A still further object is to provide a slide fastener pocket for removable leaf type fly books in which one or both sides of the pocket may be made transparent and which sides may be provided with an extra open face pocket adjacent each side of the slide fastener pocket having transparent sides so that the user may have some reinforcement for the sides of the pocket if needed and to allow for additional storage space without additional leaves being required.

These objects I accomplish with the device illustrated in the accompanying drawing in which similar numerals and letters of reference indicate like parts throughout the several views and as described in the specification forming a part of this application and pointed out in the appended claims.

In the drawing:

Figure 1 is a plan view of the pocket, leaf section opened to that side through which the articles may be seen which are carried within the pocket and showing the removable wet leaf and the net pocket for leaders.

Figure 2 is a transverse section showing the manner in which the pocket may be constructed.

Figure 3 is a bottom edge view of Figure 1.

Figure 4 is a plan view of a removable wet leaf having the leader net shown made thereon instead of in the leaf section, if desired, or the net may be made both places.

In the drawing I have shown the removable pocket A, formed in a leaf section B, having male and female snaps fasteners C in the corners thereof by which the leaf section may be inserted into a build up book of the type shown in my copending application for patent for Build up

fly book for fishermen, Serial No. 86,219, filed June 20, 1936.

The pocket A is made by taking two separate sheets of material 3 and 4, and sewing them down the middle at a seam 5, then sewing up the two ends 6 of the abutting halves 7 and 8 of the two leaves and securing the slide fastener 10 onto the outer edge of the pocket 9 formed between the two halves 7 and 8. One face 11 of the half 7 is cut away and a transparent Celluloid, Pyralin, or a sheet of like material 12 is sewed therein to make a transparent face or opening therefor. A separate sheet of like material 13 is bound on the edges at 14 and then the back side and the two ends are sewed onto the half 7 outside the transparent face 12 in the pocket to give an additional pocket and provide additional strength to the Pyralin or Celluloid 12. Onto the half 15 of the sheet 3 I then secure a net pocket 17 formed by securing a net 18 to the face of the sheet 3 by sewing binding 19 onto the net and then securing the binding to the sheet 3 along one side 20 and one end 21 and partially along the inner side 22 and the top end 23 leaving a slanting portion unsewed under which leaders or like material may be placed for storing. If it is desired to keep these leaders wet, I then provide a wet leaf E similar to the wet leaf shown in my separate application for wet leaves for fly books and secure this leaf to the leaf or sheet 3 by suitable hooks and eyes 25 or like means for removably fastening the wet leaf in place.

When the leaf is wet the leaders will remain in proper condition for fishing until the wet leaf is removed and the leader pocket exposed to the air for drying.

The wet leaf E may be provided with the leader pocket as shown at E1 in Figure 4 if desired.

Having thus described my invention I desire to secure by Letters Patent and claim:

1. In a device of the class described, the combination of two sheets of material sewed together down their medial portions, with the ends of two engaging halves of the two sheets sewed together to form a pocket therebetween; a slide fastener secured to the edges of the pocket; and suitable fasteners secured to the two sheets to permit ready removal or insertion in a fly book.

2. In a slide fastener pocket and leader pocket for fly books, the combination of two sheets of material sewed together to form a pocket between two halves of said sheets; a slide fastener secured to the edges of the pocket so formed;

and a mesh fabric secured to one of said sheets on the half of the leaf not used for the pocket, said mesh fabric being sewed down to the leaf on three sides.

3. In a leader pocket for fly books, the combination of a removable leaf; a pocket formed therein of mesh fabric in which leaders may be placed, the mesh to allow view and aeration of the articles in the pocket so formed.

4. A leader pocket for fly books comprising a mesh openwork area secured to a fly book leaf; a wet leaf to be secured adjacent said pocket to allow moisture from the leaf to pass to the contents of the pocket.

5. In a device of the class described the combination of two sheets of material sewed together to form a pocket between two halves of said sheets; a slide fastener secured to the edges of the pocket so formed; a mesh fabric secured to one of said sheets on the half of the sheet not used in forming the pocket, said mesh fabric being sewed to the sheet on two sides and part of a third adjacent side; means to secure the pocket so formed in a fly book; a transparent pocket formed on one side of said pocket; and a transparent side in said pocket to permit view of the contents of the pocket.

6. A pocket for fly books formed of open mesh material permitting aeration visibility of the contents of the pocket.

7. A removable pocket for fly books comprising a leaf having snap fasteners at all four corners by which the leaf may be secured detachably in a fly book; a like sized leaf secured medially and along the ends to said first leaf form-

ing a pocket between the two adjacent halves; a slide fastener secured to these edges by which the pocket may be closed; and a net pocket sewed into the face of one of said leaves to permit 5 full visibility of all articles placed in the net pocket.

8. A removable pocket and leaf for fly books comprising two like-shaped leaves secured together along their middle, with the edges of two 10 of the sides secured together to form a pocket; a slide fastener secured along the adjacent edges to close the pocket; another half sheet secured into the medial seam to form an extra open sided pocket alongside said pocket so formed; one side 15 of said pocket having an opening therein and a sheet of transparent material secured in said side of said pocket to give clear visibility without opening the fastener.

9. In a device of the class described, for use 20 in fly books, the combination of two sheets of material secured together by stitching down their medial portions making four leaves extending from a central meeting point with the two adjacent central leaves secured together along their ends; a slide fastener secured along the 25 opening between the two adjacent leaves forming a closable pocket therebetween; and snap fasteners secured in the four corners of the two outside leaves by which the entire device may be secured in a fly book.

10. A device as set out in claim 2 including a removable wet leaf carried between the mesh pocket and the slide fastener pocket to moisten 30 articles in the mesh pocket.

GLEN P. HEINER.
